UNITED STATES PATENT OFFICE.

HARRY W. DYER, OF NEW YORK, N. Y., ASSIGNOR TO VAN KANNEL REVOLVING DOOR COMPANY, OF NEW YORK, N. Y., A CORPORATION OF NEW JERSEY.

REVOLVING DOOR.

1,206,824.

Specification of Letters Patent.

Patented Dec. 5, 1916.

Application filed February 1, 1912. Serial No. 674,639.

To all whom it may concern:

Be it known that I, HARRY W. DYER, a citizen of the United States, residing at New York, in the county of New York and State of New York, have invented certain new and useful Improvements in Revolving Doors, of which the following is a specification.

This invention relates to revolving doors of the type comprising a plurality of wings or leaves arranged radially around an axial support.

More particularly, it relates to a type of revolving doors in which the wings or leaves are held in their normal radial position by means of spring-controlled locking devices which permit the leaves to be forced out of their normal positions when subjected to heavy pressure. Doors of this type may be aptly described as "panic-proof", and the object of the present invention is to provide a revolving door of this type in which the locking mechanisms for the door wings or leaves is so designed that the pressure against them which would result if a crowd of people attempts to force its way through the door will be effective in disengaging the locking devices and allowing the wings or leaves to swing in approximate parallelism, so leaving an open passageway for the escape of the crowd.

Other objects and advantages of the invention will appear in the course of the following description in which reference is had to the accompanying drawing forming part of this specification.

In the drawings I have illustrated two slightly different embodiments of the invention, and it will be obvious to persons skilled in the art, that various modifications may be made in the details of construction and arrangement of parts without departing from the spirit of the invention. As the invention relates only to the mechanism for locking and releasing the door wings or leaves, I have not included in the drawings the details of the door hanging devices or casing, which may be of any convenient design.

In the drawings Figure 1 is a vertical section through the axis of a revolving door provided with locking mechanism embodying the present invention; Fig. 2 is a partial vertical section through the axis of the

door showing on larger scale the mechanism shown in the middle portion of Fig. 1; Fig. 3 is a vertical section on the same scale as Fig. 2 showing the arrangement of the collars which carry the leaf supporting arms; Fig. 4 is a vertical section showing in detail the form of hinge preferably employed for mounting a door leaf on its supporting arms; Fig. 5 is a top plan view of the spider for locking the door leaves at the top of the door, with the central sleeve which carries the weight of the door shown in section; Fig. 6 is a transverse section on the planes X and Y of Fig. 2; Fig. 7 is a detail view of a part of the mechanism for releasing the locking mechanism; Fig. 8 is a horizontal section on the scale of Fig. 7 on the plane Z of Fig. 2; Fig. 9 is a detail view of the pawl and ratchet mechanism for holding the locking devices in inoperative position; Fig. 10 is a detail view showing the position of the door leaves or wings in parallelism; Fig. 11 is a bottom plan view of the spider for locking the door leaves at the bottom; Fig. 12 is a horizontal section through the axis of a door having a modified form of locking mechanism; Fig. 13 is a detail view in vertical section of the form of spring support employed in the modified form of the invention; Fig. 14 is a detail view in vertical section showing the type of lock releasing device used in the modified form of the invention; Fig. 15 is a top plan view of the section locking spider in the modified form of the invention; Fig. 16 is a bottom plan view of the spider used to lock the door leaves at the bottom in the modified form of the invention, and Fig. 17 is a detail view in vertical section of the bottom spider and associated structures in the modified form of the invention.

Referring to the drawings by the reference characters, 1 designates a vertical sleeve which carries the weight of the revolving door. This sleeve may be designated for convenience as the supporting sleeve. It is slotted near the top so that the spider 2 which serves as a lock for the upper ends of the door sleeve may be fitted over it. The spider 2 is provided with four arms 3 each of which carries on its under surface a plurality of rounded projections 4 which engage suitably shaped sockets in the upper ends of the door leaves. The spider 2 is

screwed onto an internal sleeve 5 extending downward within the supporting sleeve 1. This sleeve 5 is screwed at its lower end and into a block 6, which is inclosed within the 5 supporting sleeve and to this block are attached a plurality of spring supporting brackets 7 which extend outward through vertical slots in the supporting sleeve 1. A plurality of tension springs 8 are carried by 10 the brackets 7 and are attached at their lower ends to brackets 9 similar to the brackets 7. These brackets 9 are secured to a block 10 similar to the block 6 and are arranged to slide in slots in the supporting 15 sleeve 1. Extending downward from the block 10 and secured thereto is an internal sleeve 11 corresponding to the upper sleeve 5. This sleeve 11 is secured by a suitable coupling to a locking spider 12 with shorter 20 arms than the spider 2 which engage the door leaves at the bottom, rounded projections 13 being provided on the arms of the spider 12 for engagement with suitable sockets in the lower edge of the door leaves. 25 A central rod, composed of two sections 9' and 10' connected together by a coupling-block 11', is loose within the sleeves 5 and 11, the lower end of section 11' being provided with a stepping-point 12' adapted to 30 be stepped into a socket 13' to center the door.

The door leaves 14 (see Fig. 10) are hinged to leaf-supporting arms 15 which extend radially from a series of collars 16 35 which are arranged to turn around the supporting sleeve 1, as best shown in Fig. 3. Each hinge comprises a pintle 17 secured in one of the leaf-supporting arms and a suitable pair of hinge butts 18 which are fitted 40 onto the ends of the pintle.

When the door leaves are in their normal radial position, as shown in Fig. 5, the locking spiders 2 and 12 are normally held in locking engagement with the door leaves by 45 the tension of the springs 8. The locking engagement of the projections on the spider, owing to the rounded form of the projections thereon, is not such as to lock the door leaves rigidly, and heavy pressure exerted against 50 the door leaves will force the locking members out of engagement with the leaves and permit the leaves to be swung into parallelism as shown in Fig. 10. To permit the release of the door leaves from locking engagement 55 with the spider without applying force to the leaves themselves, I provide the releasing mechanism shown in Figs. 2, 7 and 8. A transverse shaft 19 extends through the axis of the door and is supported in suitable 60 bearings 20 on the inside of an external sleeve 21 which encircles and forms a casing for the springs 8 and associated structures. This sleeve 21 is attached to the supporting sleeve 1 in any suitable manner and similar 65 sleeves 22 and 23 are provided above and

below the leaf-supporting arms respectively. Near each end of the shaft 19 and rigidly secured thereto, I provide a member 24 presenting a pair of oppositely arranged arms. These arms are connected by links 25 with 70 U-shaped brackets 26 which are attached to the blocks 6 and 10, as best shown in Fig. 2. By a partial rotation of the shaft 19, the links 25 and the brackets 26 are forced into the position shown in dotted lines in Fig. 7, 75 thus overcoming the tension of the springs 8 and forcing the locking spiders out of engagement with the door leaves, as will be readily understood from examination of Fig. 1. To facilitate the turning of the 80 shaft 19, it is provided with squared extensions 27, as shown in Fig. 9, to receive a wrench. Adjacent to the squared extension of the shaft 19, I provide a small ratchet 28 and supply a pair of pawls 29 to coöperate 85 therewith. These pawls lock the ratchet against rotation and prevent the spiders 2 and 12 from moving into engagement with the door leaves until the pawls are released and the springs 8 allowed to act. 90

In the modified form of the invention illustrated in Figs. 12 to 17 inclusive, I have provided locking spiders arranged in sections which are independently movable. This construction is designed to permit the 95 release of each door leaf singly without disturbing the others. The upper spider comprises a plurality of independent arms 30 which may be connected by dove-tail joints, as shown, or in any other suitable manner. In 100 like manner the lower spider is composed of a plurality of independent arms 31, as shown in Fig. 16. The spiders are arranged to slide vertically on the door supporting sleeve 1, as in the form of the invention 105 first described, but each spider arm is secured to an independent supporting member 33. These supporting members are arranged within the sleeve 1 and are secured against separation by dove-tail joints or 110 otherwise, but each is slidable independently of the others. The members 33 are arranged in two sets, the lower set carrying the arms of the lower locking spider and the upper set carrying the arms of the upper locking 115 spider. Attached to the upper set of members 33, near their lower ends are a set of springs supporting brackets 34, as shown in Figs. 12 and 13. Each of the brackets 34 has a curved arm or lug projecting laterally 120 therefrom. These arms 35 are arranged in pairs as shown in Fig. 12 for reasons that will presently appear. A similar set of brackets is provided at the upper ends of the lower set of members 33 and the two sets of brackets are connected by means of tension springs 8 as in the first form of the invention. To force the brackets of the upper set away from those of the lower set 125 against the tension of the springs 8, I pro- 130

vide separating or releasing devices of the form shown in Fig. 14. Into the underside of the lug 35 on each of the upper brackets 34, a rod 36 is screwed and a similar rod is 5 screwed into the upper side of each lug 35 of the lower set of brackets. The adjacent ends of these rods 36 extend through openings in screw sockets 37 attached to the outer surface of the door supporting sleeve 10 1 and a screw 38 with a tapered end is mounted in each socket 37 so that the tapered end of the screw may be forced between the adjacent ends of each pair of rods 36. The outer end of each screw 37 is squared 15 to receive a socket wrench and the casing sleeve 23 has an opening adjacent to each of the screws 37 to permit the insertion of the wrench, as shown in Fig. 14.

From the foregoing description of the 20 modified form of my invention it will be seen that the separation of one pair of brackets 34 will result in the release of only one door leaf; but if a crowd surging against the door in an attempt to escape the pressure against the door leaves will force the 25 locking members on the spiders out of engagement with the door leaves and permit the leaves to swing as in the form of my invention first described.

30 What I claim is:

1. A revolving door having in combination, an axial supporting member, a plurality of one part wings, arranged to swing independently about the supporting member, a vertically movable yielding locking spider at the top of the door, and in engagement with the wings thereof, whereby, upon the application of abnormal pressure to the wings, the spider will yield to permit the 40 wings to fold.

2. A revolving door having in combination, an axial supporting-member, a plurality of one part wings arranged to swing about the supporting-member, a sectional spider and an engaging connection, yieldable under abnormal pressure, between each arm of the spider and the upper edge of each wing, each section of the spider being vertically-movable, so that each wing may 50 be independently movable of the others.

3. A revolving-door having in combination, an axial supporting-member, a plurality of wings arranged to swing about the supporting-member, a vertically-movable locking-spider carried by said supporting-member, engaging means, yielding under abnormal pressure, between the upper edges of the wings and the arms of the spider, means for exerting a constant pressure to 60 hold the wings into engagement with the spider arms, and means for releasing such pressure.

4. A revolving-door having in combination, an axial supporting-member, a plurality of wings arranged to swing about the 65

supporting-member, a sectional spider, an engaging connection, yieldable under abnormal pressure, between the upper edges of the wings and the arms of the spider, means for exerting a constant pressure to hold the 70 wings into engagement with the spider sections, and means for releasing such pressure.

5. A revolving door having in combination an axial supporting member, a plurality of wings arranged to swing about the 75 supporting member, yielding means engaging the upper and lower portions of the wings to hold them in radial position with respect to the supporting member, but adapted to be forced apart by the application of abnormal pressure, so that the wings may be released and folded to make a passageway, upon the application of abnormal pressure.

6. A revolving door having in combination, an axial supporting-member, a plurality of wings arranged to swing about the supporting member, locking members engaging the upper and lower portions of the wings to hold them in normal radial position with respect to the supporting-member, yielding means connecting the locking means which permits the locking means to separate yieldingly to disengage the wings to permit them to fold upon the application 95 of abnormal pressure.

7. A revolving door having in combination, an axial supporting member, a plurality of wings arranged to swing about the supporting member, a vertically movable 100 locking spider at the top of said wings, and in yielding engagement with the upper portions of said wings, the locking spider being adapted to yield when excessive pressure greater than that necessary to revolve the 105 door in ordinary operation, is applied to the wings, to permit said wings to fold, and means for exerting a constant pressure to hold the locking spider in engagement with said wings.

8. A revolving door, having in combination an axial supporting-member; a plurality of wings arranged to swing about the supporting-member; a locking-member arranged to yieldably engage the upper edges 115 of the wings, a locking-member arranged to yieldably engage the bottom edges of the wings; upper and lower blocks connected with the respective locking-members, and means connecting the blocks together, whereby said locking-members are held in yielding engagement with the upper and bottom edges of the wings.

9. A revolving-door, having in combination an axial supporting-member; a plurality of wings arranged to swing about said supporting-member; vertically movable locking-members adapted to yieldably engage the upper and lower edges of the wings; upper and lower blocks carried by 120 125 130

the locking-members, and springs between the blocks for holding the locking-members into yieldable engagement with the wings.

10. A revolving-door having in combination an axial supporting-member, a plurality of wings arranged to swing about said supporting-member; a locking member carrying a depending sleeve and provided with means yieldably engaging the top edges of 10 the wings; a block connected to the lower end of the sleeve and having arms projecting through slots in the supporting-member, and connected with said arms for exerting a constant pressure to hold the locking-member into yieldable engagement with the wings.

11. A revolving-door, having in combination an axial supporting-member; a plurality of wings arranged to swing about said 20 supporting-member; a vertically-movable

locking-member carrying a depending sleeve and provided with means yieldably engaging the upper edges of the wings; a block connected to the lower end of the sleeve; a vertically-movable locking-member carrying an upwardly-extending sleeve provided with means yieldably engaging the bottom edges of the wings; means connecting the locking-members together, so as to hold both locking members in yieldable engagement with the wings, and means for moving the locking-members away from each other. 25 30

In testimony whereof I affix my signature in presence of two witnesses.
